UNITED STATES PATENT OFFICE

2,259,692

AUTOMATIC SELF-ADJUSTING TROUSERS
HANGER AND CREASER

Emery Hegedus, New York, N. Y.

Application February 19, 1940, Serial No. 319,625

6 Claims. (Cl. 223—95)

This invention relates to trousers hangers, and has for its main object to provide a device of this character operating on a novel principle and being more efficient, more reliable, and quicker in action than the devices now in use for such purpose.

Another object of this invention is to provide a trousers hanger of the character mentioned, which will automatically catch and hold the trousers and which will be self-adjusting to different widths of trousers.

Still a further object of my invention is to provide a trousers hanger as characterized hereinbefore, which will be adapted to engage the usual crease in the trousers and preserve and restore it, so that the hanger may act also as a creaser for the trousers.

Other objects of this invention will be apparent as the specification of the same proceeds, and among others I may mention: to provide trousers hangers and creasers of the type mentioned, which will be simple in construction, inexpensive to manufacture, easy to use, and durable.

In the drawing forming a part of this specification and accompanying the same:

Fig. 1 is a front elevation of my trousers hanger and creaser in an inoperative resting position;

Fig. 2 is an end elevation thereof;

Fig. 3 shows the upper portion of trousers suspended on my device;

Fig. 4 is a sectional view, the section being taken on the line 4—4 of Fig. 3, construction of the trousers shown being simplified and made more or less diagrammatic, the top layer of material at the cuffs and the seams having been omitted from Fig. 4 for the sake of simplicity and clearness;

Figs. 5 and 6 are fragmentary details indicating the adjustment of a coil spring used in my device;

Fig. 7 is a fragmentary section on an enlarged scale showing one element of my device inserted in one end of a trouser, the section being the same as in Fig. 4.

Referring now to the drawing more in detail by characters of reference, my trousers hanger and creaser is generally indicated by the numeral 10 and is composed of three main elements, namely, a central relatively stationary hook device proper 11, a link mechanism 12 at the lower end of said hook device, and a coil spring 13 between said stationary hook device and the movable link mechanism 12.

The hook device 11 has the usual hook 14 at 55

its upper end, whereby the trousers hanger and creaser may be suspended from a bar in a closet or from any appropriate element, as usual. Hook 14 is continued in a stem 15, the lower end of which is made flat and wide, as at 16.

A right hand and a left hand arm 17 and 18, respectively, are pivoted at the lower end of the flat portion 15, as indicated at 19.

A slideable element 20 is arranged on the lower part 15a of the stem 15, said element being composed of a transverse plate 21, a projecting upper ear 22, and a lower ear 23, in the center thereof, said ears having appropriate registering holes through which the stem portion 15a passes, whereby the plate 20 may slide upwardly or downwardly on the stem 15.

Left hand and right hand link members 24 and 25, respectively, are arranged between the sliding element 20 and the respective left hand and right hand arms 18 and 17, upper and lower pivots 26 and 27 being arranged between the said link members, the sliding element 20, and the arms 17 and 18, respectively.

A down hanging pivoted double fork member 28 is arranged at the outer end of each arm 17 and 18, said double fork member being formed of two inner branches 29 secured to one another as by welding, riveting, etc., and two outer branches 30, the respective branches being connected by the curved upper portions 31, or preferably being made of one integral bent metal piece, each. The lower ends of the inner branch 29 are somewhat separated, and the outer ends of the respective arms 17 and 18 are pivotedly arranged thereon, as indicated at 32. The outer branches 30 are covered most of their lengths by tight fitting rubber sleeves 33.

The coil spring 13 is arranged between the upper plate 22 on the sliding member 20 and a pin 34 secured into the stem 15, one of the upper coils of the spring 13 engaging the pin 34.

The use and operation of my device is practically obvious from the drawing and from the herein description, but I want to offer the following remarks to more clearly explain the same:

When it is desired to use my device and to secure a pair of trousers thereon, the two arms 17 and 18 thereof will be swung upwardly, as indicated by the arrows 17a and 18a, and my device 50 will assume the position as generally indicated in Fig. 3.

In that position, spring 13 will be compressed to a desired degree, depending on the amount of upward swing for the arms 17 and 18, and, naturally, spring 13 will have a strong tendency to

push the sliding element 28 downwardly, and thereby return the arms 17 and 18 to their normal, more or less horizontal position, as will be obvious.

In the position indicated in Fig. 3, which I may call the compressed or folded position, the four branches 30 of the two swingable or pivoted outer elements 28 of my device will be inserted in the respective four creases 35 of the lower outer ends 36 of the pair of trousers 37, as indicated in Figs. 3 and 4, and thereupon the retaining hold on the arms 17 and 18 will be released, and they will be swung outwardly under the pressure of the spring 13, members 30 being tightly pressed into the respective creases and firmly suspending the trousers on my device through said pressure and through the friction between the rubber coating 33 on the members 30 and the material of the trousers.

When it is desired to remove the trousers from my hanger, the outer members 28 will be moved inwardly by swinging the arms 17 and 18 in an inward direction.

Normally, the spring 13 is in a set position with relation to the pin 34 on the stem 15. When it is desired to increase the pressure of the spring and thereby of my device on the trousers, the spring 13 will be rotated and will move in a screw like movement on the pin 34 in a downward direction until it may arrive to the last of its coils, as indicated in Fig. 5. On the other hand, when it is desired to lessen the pressure of the spring 13, the same may be rotated in an opposite direction and will creep upwardly on the pin 15 on account of the screw action of the coils on the pin 34, as indicated in Fig. 6.

In a word, the larger the portion of the coil spring 13 placed between the sliding element 28 and the stationary pin 34, the larger will be the pressure exerted by said spring on said sliding element at a certain inclination of the arms 17 and 18 towards each other, and the smaller the portion of said spring 13 left between the sliding element 28 and the pin 34, the less will be the said pressure.

At 38 I indicate the pattern or design of the trousers which, of course, is only one example thereof, and at 39, the usual seam of one of the trousers is indicated. As has been mentioned before, in Fig. 4 said seam is not shown, neither is shown the cuff 40 indicated in Fig. 3, since these elements have no bearing whatever on the invention or the clearer understanding thereof.

and their omissions will make the said figure clearer and easier to understand.

What I claim as new, is:

1. A trousers hanger, comprising a hook member proper whereby to suspend the trousers from an appropriate element, as usual, an element slideable on said hook, opposingly pointing arms pivoted at the lower end of said hook, link members between said arms and said sliding element, a spring member on said hook exerting a downward pressure on said sliding element and causing said arms to swing outwardly through the action of said link members, the ends of the arms being adapted to engage the insides of the open ends of the trousers.

2. In a trousers hanger, as set forth in claim 1, each end of each arm having two members, each of said members being adapted to engage one crease in the outer open end of one of the trousers legs.

3. In a trousers hanger, as set forth in claim 1, two downwardly hanging pivoted blade members at each end of each arm, each blade adapted to engage a crease in the open end of one of the trousers legs.

4. In a trousers hanger, as set forth in claim 1, means to regulate the pressure of said spring.

5. In a trousers hanger, as set forth in claim 1, a stem for said hook on which said element may slide, said spring being in the form of a helical spring around said stem, a pin secured to the upper part of said stem and being engaged by the coils of said spring, said spring being made adjustable by moving the same downwardly or upwardly, by screw action between its coils and said pin, and placing a larger or smaller portion thereof between said pin and said slideable element.

6. A trousers hanger, comprising a hook device whereby to suspend the trousers on an appropriate element, a depending stem on said hook, an expansible member at the lower end of said stem adapted to be placed into the open ends of the trousers and adapted to expand and keep said trousers stretched and frictionally engaged, a coiled spring around said stem exerting pressure on said expansible member and having the tendency to cause it to expand, a pin on said stem, said spring being adjustable by turning the same around said stem so that its coils will ride on said pin.

EMERY HEGEDUS.
